UNITED STATES PATENT OFFICE.

EDWARD LONGSTRETH, OF PHILADELPHIA, PENNSYLVANIA.

EXHAUST ATTACHMENT FOR SAFETY-VALVES OF LOCOMOTIVES.

SPECIFICATION forming part of Letters Patent No. 233,782, dated October 26, 1880.

Application filed September 17, 1880. (No model.)

To all whom it may concern:

Be it known that I, EDWARD LONGSTRETH, a citizen of the United States, residing in Philadelphia, Pennsylvania, have invented an Improvement in Exhaust Attachments for Safety-Valves of Locomotives, of which the following is a specification.

The object of my invention is to prevent the objectionable noise which accompanies the discharge of steam from the safety-valves of locomotive-engines; and this object I attain by extending a pipe from the blow-off branch of the safety-valve to the exhaust-passage or exhaust-chamber of one of the cylinders, as explained hereinafter.

The view in the accompanying drawing is a vertical section of sufficient of the smoke-box end of a locomotive-boiler to illustrate my improvement.

A is part of the smoke-box of the boiler; D, one of the cylinders of the engine, and *a* the exhaust-port, communicating, through the exhaust-passage *b*, with the exhaust-chamber *G*, the latter communicating, through the usual exhaust-nozzle, *H*, with the chimney.

K is the ordinary safety-valve, having a blow-off branch, *m*, from which a pipe, *w*, extends to the exhaust-passage *b*, so that all the

steam blown off at the safety-valve will be directed into this passage instead of being discharged into the air, as usual, the objectionable noise which accompanies the ordinary escape of steam into the air being thus prevented.

I am aware that waste steam from the safety-valve of a locomotive-boiler has been directed to the smoke-box with the view of preventing the objectionable noise referred to; but waste steam discharged into and disseminated throughout the smoke-box necessarily interferes with the draft; hence this plan is objectionable.

I claim as my invention—

The combination of the safety-valve and exhaust-passage or exhaust-chamber of a locomotive-engine with a pipe, *w*, for directing the waste steam blown off from the safety-valve to the said passage or chamber, all substantially as described.

In testimony whereof I have signed my name to this specification in the presence of two subscribing witnesses.

EDWARD LONGSTRETH.

Witnesses:

JAMES F. TOBIN,
HARRY SMITH.
